UNITED STATES PATENT OFFICE

KARL STROEDTER, OF BOCHUM, GERMANY, ASSIGNOR TO THE FIRM: GEBR. EICKHOFF,
MASCHINENFABRIK, OF BOCHUM, GERMANY

ELECTRICALLY ACTUATING MACHINERY

Application filed August 1, 1927, Serial No. 209,989, and in Germany November 10, 1926.

This invention relates to a gearing composed of an electric motor and a transmission gear which is partly or wholly enclosed in a casing. Gearings of this type are for instance employed to drive shaking conveyors or the like.

In the gearings of the character stated the motor and the casing enclosing the transmission gear are mostly mounted on a common bed or base frame. This construction, however, frequently suffers from the drawback of a displacement arising between the motor and said casing, which displacement may cause, under certain circumstances, fractures of the parts in consideration. My invention has for its object to avoid this danger. This is obtained by fixing the motor on the casing of the transmission gear, in particular by sliding it into engagement with the latter either immediately or through the intermediary of an intermediate piece. When the motor is engaged directly on the casing, the assembling and disassembling of the parts is considerably facilitated, this being of a particular importance in case gearings of the type in question are used underground in mining service. When an intermediate piece is interposed between the motor and the gear casing, this piece further may preferably serve as a fitting piece, in order to allow of motors of different dimensions to be fixed on one and the same gear casing.

In order to allow of my invention to be more easily understood, some preferred embodiments of the same are illustrated by way of example in the drawing which accompanies and forms parts of this specification.

In this drawing:

40 Fig. 1 is an elevation showing a motor which is directly fixed on the gear casing,

Fig. 2 is a top view showing a motor which is united with the casing by means of an intermediate piece,

45 Fig. 3 is an elevation, partly in section, of a third embodiment, and

Fig. 4 is a fragmentary view, partly in section, of a fourth embodiment.

Referring first to Fig. 1, the electric motor *m* is slid on the casing *g*, enclosing the

transmission gear, transversely of this casing, the connection being established by a dove-tailed guide or grooves as used for receiving splines, and the motor is secured on the casing *g* against being unfixed by screw bolts *k*¹ arranged on its upper portion. The casing *g*, in its turn, rests on a base plate *b*.

In the embodiment illustrated in Fig. 2, the motor *m* is slid from above on an intermediate piece *a*² which may have the configuration of a plate or a frame. The intermediate piece *a*², in its turn, is fastened to casing *g*.

Fig. 3 shows an embodiment, in which the motor *m* is mounted on an intermediate piece *a*³ which, in its turn, is slid on the casing *g*. In this case the motor is rigidly fixed on its lower portion on the intermediate piece *a*³ by screw bolts whilst on its upper portion it is fixed thereto by clamping screws *k*³ which at the same time may serve to clamp the intermediate piece *a*³ on the casing *g*. This may be effected for instance by the said screws *k*³ tightening a wedge-shaped bar *d* located between the casing *g* and the intermediate piece *a*³.

As shown in Fig. 4, instead of these members, special fastening means *k*⁴, *d*⁴ may be provided for between casing *g* and intermediate piece *a*⁴.

The use of an intermediate piece, as described, permits of motors of normal shape of their shell bracket and of different sizes to be mounted on one and the same casing.

To withdraw the motor *m* from the casing *g*, in all the described cases is nothing required but to unfix the upper fastening means (*k*), whilst the lower fastening means (*c*), which are difficultly accessible, may remain in place both in assembling and disassembling the motor and the casing.

What I claim and desire to secure by Letters Patent is:—

1. In a device of the character described, the combination with a transmission gear case, of a motor mounting slidable on the casing only in the direction of the longitudinal axis of the motor, and means for locking the mounting in position to form the sole support. 95

2. In a device of the character described, 100

the combination with a transmission gear case having a dovetail slide portion thereon, a motor mounting having a complementary dovetail portion thereon adapted to coact with the dovetail portion on the casing, said dovetail portions being so directed that the mounting will only be capable of sliding in the direction of the longitudinal axis of the motor, and means for locking the mounting in position to form the sole support.

3. In a device of the class described including a base frame, a transmission gear system housing having perpendicular walls mounted on said frame, a motor, means for securing said motor on one of the perpendicular walls of said housing, said motor being axially movable on said wall and solely supported thereby.

In testimony whereof, I have signed my name to this specification.

KARL STROEDTER.
